No. 644,883.

Patented Mar. 6, 1900.

M. Y. WARREN.

HAND RAKE.

(Application filed Oct. 5, 1899.)

(No Model.)

UNITED STATES PATENT OFFICE.

MYLES YOUNG WARREN, OF PHILADELPHIA, PENNSYLVANIA.

HAND-RAKE.

SPECIFICATION forming part of Letters Patent No. 644,883, dated March 6, 1900.

Application filed October 5, 1899. Serial No. 732,631. (No model.)

To all whom it may concern:

Be it known that I, MYLES YOUNG WARREN, of Philadelphia, (Germantown,) in the county of Philadelphia and State of Pennsylvania, have invented a new and Improved 5 Hand-Rake, of which the following is a full, clear, and exact description.

The invention relates to farm and garden implements; and its object is to provide a new 10 and improved hand-rake arranged to permit of conveniently and quickly discharging the gathered material from the teeth of the rake.

The invention consists of novel features 15 and parts and combinations of the same, as will be fully described hereinafter and then pointed out in the claims.

A practical embodiment of my invention is represented in the accompanying drawings, forming a part of this specification, in which 20 similar characters of reference indicate corresponding parts in all the views.

Figure 1 is a plan view of the improvement. Fig. 2 is a side elevation of the same. Fig. 25 3 is a like view of the same, with the cleaner in a discharge position; and Fig. 4 is a plan view of the cleaner.

The rake on which the improvement is applied consists of the usual handle A, a cross-bar or back B, carrying spaced teeth C, and 30 a suitable brace D, extending from the handle to the cross-bar or back B, as indicated in the drawings. On the teeth C of the rake is movably held a cleaner E, preferably in the form of a link made from a single piece of 35 round iron or wire and normally held in an uppermost position by a spring-lever F, so that the cleaner E when in this position does not interfere with the gathering and accumulation of hay, grass, or other material.

40 The lever F is preferably made from a single piece of wire bent to form two oblique arms, each having a loop F', engaging the cleaner E, as is plainly shown in the drawings, and each arm has two members F² F³, of which the members F² are secured by a staple G to one side of the rake-handle A, the extreme end of the member being formed with a transverse lug driven into the rake-handle. The other members F³ extend over a 45 cross-arm H, carried by the rake-handle, said cross-arm being the fulcrum for the lever F. The connecting end F⁴ of the members F³ of

the lever is adapted to be locked to the top of the handle A by a ring or loop I, fulcrumed on the under side of the handle, so as to hold 55 the loops F' of the lever in an uppermost position, together with the cleaner E. (See Fig. 2.)

Now when the operator swings the ring or loop I out of engagement with the connecting 60 end of the members F³, then the resiliency of the spring-lever causes a downward movement of the cleaner E to slide the latter on the teeth to nearly the lower ends thereof, thus moving all the gathered material off the 65 rake. The upward swinging movement of the members F³ of the lever F is limited by a link or loop J, fulcrumed on the handle A, somewhat at the rear of the fulcrum bar or rod H. By this arrangement the cleaner E 70 is not liable to be moved off the teeth C of the rake.

After the material is discharged the operator simply presses the connecting end F⁴ of the members F³ downward to swing the lever 75 F upward and to move the cleaner E back into an uppermost normal position. The end F⁴ is then locked in place on the top of the handle A by the loop or ring I. The rake is now again in condition for using it for its legitimate purpose—that is, for gathering the material—and when a desired quantity of material has accumulated on the rake then the operator swings the loop or ring I rearward to release the lever F and again move the cleaner 85 E downward to discharge the accumulated material from the rake-teeth.

Having thus fully described my invention, I claim as new and desire to secure by Letters Patent—

1. A rake, provided with a cleaner movable on the teeth of the rake, a spring-lever fulcrumed on the rake and engaging said cleaner, to move the latter up or down on the rake-teeth, and means for locking said spring-lever, to hold the cleaner in an uppermost position, substantially as shown and described. 95

2. A rake provided with a cleaner movable on the teeth thereof, a spring-lever fulcrumed on the rake and provided with oblique arms engaging the cleaner, and means for locking the spring-lever to the rake-handle, substantially as described. 100

3. A rake provided with a cleaner movable

on the teeth thereof, a spring-lever fulcrumed on the rake and formed with oblique arms, each having a loop through which the cleaner passes, and means for locking the spring-lever to hold the cleaner in an uppermost position, substantially as described.

4. A rake provided with a cleaner movable on the teeth thereof, a spring-lever bent to form oblique arms engaging the cleaner and each formed of two members, one of which is fixedly secured to the rake-handle, and means for detachably locking the connecting end of the other members to the rake-handle, substantially as described.

15 5. The combination with a rake provided with loops fulcrumed on its handle and with a cross-arm projecting from opposite sides of

its handle, of a cleaner in the form of a link through which the teeth project, and a spring-lever bent to form oblique arms, each having a loop at its end through which the cleaner passes, and formed of two members, one member of each arm being fixedly secured to the rake-handle and the other members of the arms being connected, the connected end of the said members extending through one loop of the handle and adapted to have the other loop of the handle swung over it, substantially as described.

MYLES YOUNG WARREN.

Witnesses:
